UNITED STATES PATENT OFFICE.

MARTIN L. KEYES, OF FAIRFIELD, MAINE, ASSIGNOR TO KEYES FIBRE COMPANY, OF SHAWMUT, MAINE, A CORPORATION OF MAINE.

PACKAGING-MACHINE.

No. 921,256.

Specification of Letters Patent.

Patented May 11, 1909.

Application filed June 2, 1906. Serial No. 319,838.

To all whom it may concern:

Be it known that I, MARTIN L. KEYES, a citizen of the United States, and a resident of Fairfield, in the county of Somerset and 5 State of Maine, have invented an Improvement in Packaging-Machines, of which the following description, in connection with the accompanying drawing, is a specification, like letters on the drawings representing like 10 parts.

This invention relates to a machine for bundling articles, and is especially designed for use in putting up packages of pulp or paper pie plates and similar articles. Such 15 articles when put up by the use of this machine are stacked in piles or rolls of the desired number, as five hundred, wrapped in heavy paper, and tied with twine running longitudinally and transversely around the 20 pile or roll. Plates or similar articles when packed in such a package are easily handled and take the minimum amount of room; the packaging materials are cheap and light and the whole package presents the most satis- 25 factory form for shipping purposes. In bundling plates and similar articles into such a package it is necessary that the pile or roll should be compacted as much as possible so as the bundle will occupy the smallest space 30 possible, and also retain its shape and not contract under pressure or handling to allow the plates or other articles to become released from the covering.

The machine of the present invention is 35 designed to take the plates or similar articles in a loose pile or stack, align them, compact them into a firm, solid roll, and retain them in this condition until the paper or wrapping material has been placed around 40 them, and the binding twine placed around the roll longitudinally one, two or more times, and firmly tied to retain them in their compacted form.

The construction of the machine whereby 45 these ends are secured as embodied in the preferred form of the invention will be seen from the accompanying specification and drawings, and the invention will be more particularly pointed out in the appended 50 claims.

The drawings represent the preferred form 55 of the machine which has been devised embodying the invention, the separate ends of the machine being shown with the intermediate portion broken away.

In the drawings, Figure 1 is a reduced perspective view of the pile or roll of pie plates in its bundled form ready for shipping; Fig. 2 is a side elevation of the upper portion of the right-hand end of the machine, partly in cross-section and showing the end plates of a pile or roll in position; Fig. 3 is a side elevation of the upper portion of the left-hand end of the machine showing a few of the plates at the opposite end of the roll in position; Fig. 4 is a face view of the right-hand end showing the bundling strings or cords in position before the pile or roll of plates is placed in the machine; Fig. 5 is an end elevation of the upper portion of the right-hand end of the machine.

The supporting standard of the machine comprises a bed portion A extending longitudinally and of any desired length determined in general by the length of the rolls or 75 packages to be formed in the machine, and supporting legs A' therefor oppositely disposed at each end of the bed and bolted thereto by the bolts A².

A pair of oppositely disposed longitudinally adjustable head supports are mounted upon the bed at each end thereof. The right-hand head support B has a depending rib B' fitting in a longitudinal groove A³ in the bed whereby the head support is guided 85 in its longitudinal adjustment. The head support is clamped in position by a bolt B² extending through a transverse recess in the bottom of the head support and provided with oppositely disposed clamp blocks B³ 90 beveled as indicated in Fig. 5 above and below the clamping bolt to engage corresponding bevels on the base of the head support and the top of the bed. The clamping bolt B² is provided with a handle B⁴ whereby it 95 may be tightened up and the head support may thus be adjusted and locked in its adjusted position longitudinally of the bed. The left-hand head support C is similarly 100 constructed and capable of similar adjustment and locking in adjusted position as illustrated in Fig. 3, and it is therefore not necessary to again describe the details of the construction.

The right-hand head support carries the 105 head D, which as illustrated in Fig. 4 may be of a skeleton-like form and is herein shown as conforming to the exterior surface of the pie plate. The particular form which the head shall take depends upon the form of the arti- 110

cles forming the pile or roll. The head is provided with intersecting grooves D' , D'' , of a number corresponding to the number of cords which are to be passed longitudinally 5 around the roll or pile and herein shown as two. These grooves must be sufficiently deep so that when the head is pressed against the pile the cords can be moved freely there-through and tied tightly around the pile.

10 The head D has a projecting journal or pin D^3 by which it is loosely mounted in the end of the shaft D^4 . The head D may therefore be readily removed and replaced with a head of any desired size or configuration according 15 to the articles to be packaged.

The shaft D^4 is keyed by the key D^5 and the groove D^6 to the longitudinal arm B^5 of the head support, and is slid back and forth therein carrying the head D by means of the 20 screw D^7 operated by the hand-wheel D^8 . By these means the head D may be forced toward the opposite head to compact the pile of plates or other articles, the hand-wheel and screw allowing of great pressure 25 being produced upon the pile.

The opposite head E is constructed in similar but complementary form to that of the head D , and need not be further described. Its projecting journal or pin E^3 is shown as 30 mounted directly in the arm C^5 of the supporting head C , because under ordinary circumstances there is no need of providing for the screw feed of both heads, but such construction could be duplicated if desired in 35 connection with the head E .

The number of grooves in the face of the heads is dependent upon the number of longitudinal strands of bundling cord to be passed longitudinally of the bundle. Under 40 some circumstances one might be sufficient, but two are preferred because the bundle is then held securely. The grooves should preferably be in the faces of both heads to allow of the drawing of the cords tightly and 45 prevent the cords being forced into the bundle at the ends, but it is obvious that the advantages of this feature of the invention may be secured by having but one head grooved, it being possible to tighten up the cords and 50 tie the bundles securely even if they be held from movement at one end of the machine, and the claims are not to be construed as limiting the invention in this respect.

The pile or roll of plates or other articles is 55 supported in proper alignment with the heads by means of a pair of supporting bars F . These supporting bars are arranged to support the plates or other articles at two widely separated points so that the articles 60 are held in proper alignment with the axis of the heads. They are made simultaneously adjustable in such a manner that they always remain parallel with the axis of the heads but move toward and from the axis on substantially radial lines so that whatever the

diameter or size of the articles may be they are supported at two similar or symmetrically disposed points. One feature of the present invention consists in providing for the adjustment of these supporting bars so 70 that plates or other articles of various configuration and size may be packaged upon the same machine. It will be seen that if these supporting bars be moved toward and from the center of the heads and held in their adjusted position the range of the machine as to the size and configuration of the articles to be bundled or packaged is practically unlimited.

At each end of the bed of the standard are 80 provided upright frame plates G and H respectively. The frame plate G at the right-hand side of the machine is provided with two pairs of concentrically arranged slots G' , G'' . A pair of segmental plates G^3 , 85 G^4 are movably supported upon the frame plate G and guided in their movement by bolts G^5 , G^6 respectively extending into said concentric slots. A similar pair of segmental plates, one of which is indicated at H^4 in Fig. 90 3 are mounted upon the frame plate H in similar manner at the left-hand side of the machine.

The supporting bars F , herein shown as hollow tubes or cylinders, to secure proper 95 size and strength extend longitudinally of the machine and are firmly bolted to the oppositely aligned segmental plates by the bolts F' . These central plates carrying the supporting bars are arranged to move on the 100 arc of a circle and the path of movement of each bar is therefore slightly curved, but it is arranged tangential with a line radial from the axis of the heads so that the movement of each supporting bar is substantially radial 105 of the axis of the heads and consequently is symmetrically positioned on the bars with respect to the articles to be supported whatever their size or diameter.

As a preferred and suitable means for providing for the adjustment of the supporting bars the construction herein illustrated has been designed. Both segmental plates at both ends of the machine are provided with segmental toothed racks indicated at the 110 right-hand side of the machine in Fig. 5, as G^7 , G^8 . Pairs of intermeshing gears, one of which also intermeshes with each of the segmental racks, are located at both ends of the machine, those at the right-hand end being 115 indicated as K and K' , and one of those at the left-hand end being indicated as K^2 . One of each of the pair of gears at each side of the machine is mounted upon the shaft K^3 , extending lengthwise through the machine, the other member of each pair being mounted upon short trunnions or bearings K^4 , K^5 in the frame plates G , H . The shaft K^3 at the right-hand end of the machine is provided 120 with a crank handle K^6 , and this handle has 125

projecting from it to one side an arm K⁶, provided with a slot K⁷ curved concentrically with the axis of the shaft K⁸, and a locking bolt K⁹ passes through the slot K⁷ into the frame plate G. It will thus be seen that by turning the crank handle K⁵ the pairs of intermeshing gears at both ends of the machine will be rotated in opposite directions causing the movement of the segmental plates in opposite directions to carry the supporting bars toward and from the axis of the heads, and that the parts may be locked in adjusted position by screwing up the locking bolt K⁹ in the curved slot K⁷.

15 The machine is shown with the supporting bars F, F in their lowermost position adjusted for the largest size of plate or other article to be bundled on the machine, such plates being indicated at L, and in Figs. 4 and 5 the supporting bars are indicated in dotted lines F⁰, in a position much nearer the axis of the heads to support a small sized plate or article also indicated in dotted lines as L⁰, it being understood that the heads will 20 be changed if found necessary to correspond with the configuration and shape of the smaller plates or articles to be bundled.

In the operation of the machine as herein illustrated the workman will first by means 30 of the crank handle K⁵ and the locking bolt K⁹ adjust the supporting bars to their proper position relatively to the center of the head and lock them in that position. The head supports will also be adjusted by means of 35 the bolts B² and their operating handles into the proper longitudinal position on the bed to provide for the ready insertion of the roll or pile of plates or other articles between the heads and then locked in position. A sheet 40 of paper or other wrapping material will then be laid across the supporting bars and the roll or pile of plates or other articles laid on the paper on the supporting bars between the heads. Proper heads will be inserted in 45 the head supports, the cord or wrapping twine will be placed longitudinally of the roll underneath the paper, through the grooves in the heads, and then the hand wheel D⁴ will be turned to bring the heads 50 together with great power compressing and compacting the pile or roll. The paper or other material will then be wrapped around the roll or pile and the cord tied firmly longitudinally of the roll or pile while in its compressed or compacted condition. The cord 55 will then be tied circumferentially of the roll or pile, but the roll or pile may be removed from the machine when this is done if desired because the longitudinal strands will 60 hold it in its compressed or compacted condition. The bundle when finished will present the appearance substantially as shown in Fig. 1 and presents the desired form of package.

65 While various mechanisms herein illus-

trated and described are in themselves novel and particularly well adapted to the preferred form of construction embodying the invention, yet the invention in its broad aspect is not limited to the particular mechanism shown, but may be embodied in various mechanical constructions for securing the same end.

Having described my invention, what I claim as new and desire to secure by Letters Patent, is:

1. A bundling machine comprising a standard, a pair of oppositely disposed horizontally aligned heads mounted thereon, grooves in the faces of said heads to receive the bundling cords, means for forcing one head toward the other, a pair of longitudinally disposed supporting bars beneath said heads to receive and hold the articles to be bundled, and means for simultaneously raising and lowering said supporting bars without substantially varying their angular distance with respect to the axis of said heads whereby articles of various diameters may be firmly supported and brought into alignment with the heads.

2. A bundling machine comprising a standard, a pair of oppositely disposed horizontally aligned heads, a pair of longitudinally disposed supporting bars beneath said heads to receive and hold the articles to be bundled, pairs of movable end plates mounted on said standard at each end and carrying said supporting bars, means for moving said end plates simultaneously, and means for guiding said end plates to carry the bars in their movement parallel to and substantially radial of the axis of alignment of said heads.

3. A bundling machine comprising a standard, a pair of oppositely disposed horizontally aligned head supports mounted thereon, heads mounted in said supports, grooves in the faces of said heads to receive the bundling cords, means for forcing one head upon and with relation to its support toward the other, a pair of longitudinally disposed supporting bars beneath said heads to receive and hold the articles to be bundled, and means for simultaneously raising and lowering said supporting bars without substantially varying their angular distance with respect to the axis of said heads whereby articles of various diameters may be firmly supported and brought into alignment with the heads.

4. A bundling machine comprising a standard, a pair of oppositely disposed horizontally aligned head supports mounted thereon, heads mounted in said supports, grooves in the faces of said heads to receive the bundling cords, means for forcing one head upon and with relation to its support toward the other, a pair of longitudinally disposed supporting bars beneath said heads to receive and hold the articles to be bundled, means

for simultaneously raising and lowering said supporting bars without substantially varying their angular distance with respect to the axis of said heads whereby articles of various diameters may be firmly supported and brought into alignment with the heads, and means for locking the supporting bars in their adjusted position.

5. A bundling machine comprising a standard, a pair of oppositely disposed horizontally aligned and longitudinally adjustable head supports mounted thereon, heads mounted in said supports, grooves in the faces of said heads to receive the bundling cords, means for forcing one head on and with relation to its support toward the other to compress the bundle, a pair of longitudinally disposed supporting bars beneath said heads to receive and hold the articles to be bundled, and means for simultaneously raising and lowering the supporting bars without substantially varying their angular distance with respect to the axis of said heads.

6. A bundling machine comprising a standard, a pair of oppositely disposed horizontally aligned heads mounted on said standard, means for forcing one head toward the other to compress the bundle, a pair of longitudinally disposed supporting bars beneath said heads to receive and hold the articles to be bundled, pairs of segmental plates at each end of the machine carrying the supporting bars, and provided with segmental toothed racks, pairs of intermeshing gears at each end of the machine, the members of each pair of gears intermeshing with the members of the segmental plates, means for rotating simultaneously one gear of each pair to raise or lower the supporting bars as desired into proper alignment, means for locking the supporting bars in their aligned position.

of the machine, the members of each pair of gears intermeshing with the pairs of segmental plates, means for rotating simultaneously one gear of each pair to raise or lower the supporting bars as desired into proper alignment.

7. A bundling machine comprising a standard, a pair of oppositely disposed head supports mounted therein, heads mounted in said supports, grooves in the faces of said heads to receive the bundling cords, means for forcing one head toward the other to compress the bundle, a pair of longitudinally disposed supporting bars beneath said heads to receive and hold the articles to be bundled, pairs of segmental plates at each end of the machine carrying the supporting bars, and provided with segmental toothed racks, pairs of intermeshing gears at each end of the machine, the members of each pair of gears intermeshing with the members of the segmental plates, means for rotating simultaneously one gear of each pair to raise or lower the supporting bars as desired into proper alignment, means for locking the supporting bars in their aligned position.

In testimony whereof, I have signed my name to this specification, in the presence of two subscribing witnesses.

MARTIN L. KEYES.
